[57] CLAIM

The ornamental design for a Christmas tree figurine, substantially as shown.

DESCRIPTION

FIG. 1 is a front elevational view of a Christmas tree
figurine showing my new design;

FIG. 2 is a side elevational view thereof as viewed from the left side of FIG. 1;

FIG. 4 is a top plan view thereof;

FIG. 5 is a back elevational view thereof; and

FIG. 6 is a bottom plan view thereof.
